TAR REFINING

Application filed December 11, 1928. Serial No. 325,190.

This invention relates to the refining of tars which are obtained from minerals such as lignite, shale, coal, and the like, by distillation or by any method other than distillation, such as extraction by solvents.

While processes for the coking or distillation of lignite, shale, coal, and the like, have been so improved and developed as to produce coke that is better in quality and

10 constitutes a better yield from the raw material and to produce tar that constitutes a better yield from the raw material and contains constituents of greater value than the constituents of tars heretofore produced, the 15 art of extracting from such tars the maximum quantity of valuable products in a condition in which they possess their maximum value has not been developed. Laboratory experiments have indicated the presence in

20 such improved tars of some valuable products, but the methods of refining to which these tars have been subjected have degraded or destroyed the valuable constituents thereof so indicated to be present, and 25 the value of the final products obtained by such methods has hardly been sufficient to warrant the recovery of such products as have been obtained from tars by former methods. For example, such tars contain

30 highly valuable high-viscosity lubricating constituents as well as less valuable lubricating constituents of lower viscosity and contain amorphous wax as well as crystalline wax; but the former impossibility of removing such amorphous wax to an extent sufficient 35 to produce low cold test lubricants of high viscosity, led to the practice of subjecting the tar to conditions that would convert all of the wax present therein to crystalline

40 form in order that it might be removed by the well-known filter-pressing operations that are inapplicable to the removal of amorphous wax. The result of this practice was that tar was subjected to destructive distillation

45 in order to convert all of the wax present into crystalline wax to the end that it might be removed by known practice, and this operation degraded the lubricating constituents present and only low viscosity lubricating oil of 50 relatively low value was obtained. Great

effort has been made to convert such low viscosity lubricants so obtained into useful and valuable lubricants, as by subjecting such light lubricating products as the tar refineries were able to produce with a low enough cold test to polymerization and condensation under pressure or in the presence of catalysts, such as metal chlorides, but these efforts produced at best only inferior lubricants.

Moreover, the treatment applied to tar for the purpose of converting the contained wax into crystalline wax in order that its removal might be possible, not only degraded the constituents valuable as lubricants but reduced the wax content and increased the proportion of oils of low value, such as so-called Diesel oils or burning oils, thus further reducing the value of the final product.

In addition to the former inability to remove wax from the lubricating constituents of tar to a desired degree without reducing the proportion and impairing or destroying the value of the constituents of the tar, the presence in tars of constituents not substantially found in crude petroleum has prevented the obtaining of the important constituents of tar in full proportion and in valuable condition. Thus, tars contain substantial quantities of resins, organic basic substances such as pyridine and the like, and organic acid substances, such as phenols, which have industrial value when isolated, but which because of their presence in tar have deterred or prevented skilled petroleum refiners from successfully refining tars by the application of the skill and knowledge of their calling. Furthermore, the mere application of the special operations, herein described, whereby the previously impossible dewaxing of tar products to a sufficient degree is nevertheless successfully achieved with the production of low cold test products, do not produce satisfactory dewaxed products from all tars. In other words and more particularly, it has previously been impossible to dewax constituents of tar that contain lubricating oil of high viscosity, without degrading the lubricating oil content thereof, but in accordance with this invention it is possible to dewax such constituents sat-

isfactorily without degrading the lubricating oil constituents thereof, but the mere application of such improved dewaxing operations may produce, particularly from tars obtained from lignite by low temperature distillation, products which tend to oxidize or polymerize or solidify spontaneously. Accordingly operations must be applied and effects must be obtained in the refining of tars which have no counter-part or suggestion in petroleum refining.

It is an object of this invention to provide a process whereby the valuable products in tars may be simply and economically obtained in their valuable form with a minimum of loss and a minimum degradation of valuable products into the less valuable products. A specific object of this invention is to provide a process whereby a maximum quantity or proportion of lubricating oil of low cold test and of relatively high viscosity and substantially free of contaminating substances and substantially free of a tendency to oxidize or polymerize spontaneously is obtained from tars, particularly tars obtained by low temperature distillation from lignite, shale, coal, and the like, and especially tars so obtained from lignite. A further feature of this invention is that there are produced in the practice thereof separate bodies of wax, one of which constitutes a high grade crystalline wax, and the other of which constitutes a high melting point hard amorphous wax. Also, in the practice of this invention resins present in the tar, and particularly resins that solidify spontaneously presumably by oxidation or polymerization, are obtained as a separate product, as are creosotes and organic basic substances. In the practice of this invention the several products may be obtained in one or more parts having differing characteristics. Thus the lubricating oil may come from the last treatment in a single body having medium viscosity and from which lubricating oils of varying viscosity may be produced, or the lubricating oil may be produced in several parts having varying viscosity, and the creosotes may all be recovered together or may be recovered in parts having varying viscosity. Other separate products obtained in the practice of this invention are naphtha, and burning oils, resins and pitch. The low cold test lubricating oil obtained by this process is comparable in quality and yield to similar products obtained from petroleum, and it is obtained without any artificial or synthetic treatments, and it may be divided, particularly by no-cracking distillation, into fractions having any desired properties, including so-called heavy lubricants such as cylinder stock.

In the practice of this invention various specific modes of procedure may be followed, each of which results in obtaining a maximum proportion of lubricating oil in sub-

stantially the condition in which it existed in the tar except that it has been dewaxed to a desirable extent and freed of undesirable constituents of the tar, and a maximum proportion of wax in substantially the condition in which it existed in the original tar except that it has been separated into a crystalline fraction and an amorphous fraction and is preferably freed of undesirable constituents of the tar. Thus, in the practice of this invention there may be obtained from the tar by carefully performed non-destructive distillation, in which both steam and vacuum may be employed to attain the desired end, a single fraction which alone contains, or two or more fractions which together contain, substantially all of the wax of the original tar in the form in which it existed in the tar and substantially all of the lubricating oil of the tar in substantially the form in which it existed in the tar, such fraction or fractions being substantially free of resins. Also, in the practice of this invention there are obtained one or more lubricating-oil-containing fractions containing wax that is as a whole sufficiently crystalline to be removable by filter-pressing and one or more lubricating-oil-containing fractions containing wax that is as a whole not removable by filter-pressing and is substantially amorphous in form, and then such fractions are dewaxed by methods capable of removing wax having the characteristics of the wax contained in them.

In the practice of this invention such fractions may be produced directly from the tar by careful distillation or a single fraction containing substantially all of the wax and substantially all of the lubricating oil and substantially free of resins may be produced from the tar and then fractionated by careful distillation into fractions containing only crystalline wax or only wax that is not removable by filter-pressing.

An important feature or characteristic of this invention is that in preparation for dewaxing there are produced from the tar by careful distillation which causes a minimum of degradation of valuable products, one or more fractions containing only filter-pressible wax and one or more fractions containing only non-pressible wax, said fractions together containing substantially all of the wax and all of the lubricating oil of the original tar in substantially the form in which they existed in the original tar except that said fractions are substantially free of resins although they may contain organic acid and basic substances and coloring matter.

If the tar refined in accordance with this invention contains but a small proportion or is free of resins, as in the case of some tars obtained from shale, the fraction that contains wax and lubricating oil, or the last por-

tion or fraction of such a fraction may be a residue; but if the tar contains a substantial quantity of such resins, as in the case of tars obtained by low temperature distillation of lignite, it is an important feature of this invention that even the heaviest lubricating-oil-containing portion of the tar will be removed therefrom by distillation and care will be exercised to prevent any substantial quantity of resins from distilling over into any distillate from which dewaxed lubricating oil is to be obtained. The point at which the cut is made to prevent resins from distilling over with lubricating oil may be determined empirically. For example, the temperature at which the cut must be made to prevent resins from distilling over may be determined by testing the distillate by rubbing it between the fingers and by determining the stability of the distillate stream against spontaneous formation of gummy substances. Liquid that feels gummy or in which gummy substances are spontaneously formed is too rich in resin to be passed into the distillate that is to be dewaxed.

In the practice of this invention organic acid substances such as creosote are removed from lubricating-oil-containing fractions with a relatively strong solution of caustic soda, thereby causing the precipitation of a dark sludge-like substance which upon removal from the oil may be decomposed by acid to free the creosote. In such treatment small quantities of resins may be removed but it is preferable that the proportion of resins shall be as small as possible because the presence of such resins promotes emulsification that impairs the separation from the oil of phenolates, such as creosote salts.

It is to be understood that in the combined practice of several features of my invention, my invention is not limited to the removal of organic acid substances by caustic soda but includes removal thereof by extraction by means of solvents such as alcohol.

If organic acid substances are removed in the practice of my invention, by treatment with caustic soda, the residual liquid remaining after the removal of the resulting precipitate, is washed with water; and that water is preferably added to the precipitate prior to decomposition of the phenolates with acid for the recovery of the organic acid substance.

In the practice of this invention it is preferable that prior to the removal of organic acid substances, organic basic substances be removed; and this can be accomplished by a mild acid treatment that separates out the organic basic substances in the form of a sludge-like precipitate.

In the practice of my invention the removal of organic acid substances and organic basic substances may be effected prior to dewaxing or subsequently to dewaxing. If they are removed prior to dewaxing they can be

removed from separate fractions that contain wax and lubricating oil or they may be removed from a single fraction that contains wax and lubricating oil and is produced either as a result of a single distillation or by bringing together a plurality of such fractions produced by distillation. If all of the material from which organic acid substances and organic basic substances are to be removed, exists or is brought into a single body, then that body must be divided before dewaxing into one or more fractions that contain only crystalline wax and one or more fractions that contain only non-pressible wax.

If basic substances and organic acid substances are removed in the practice of my invention from dewaxed products obtained from tar, then the dewaxed products may be brought together for that purpose or those substances may be removed from a separate body of oil dewaxed by filter-pressing and from a separate body of oil produced by removal of amorphous wax, or from several of each of such bodies.

In the practice of my invention the first fractions obtained from the tar will consist of raw naphtha and burning oils and there will be produced one or more fractions containing only crystalline wax and one or more fractions containing only non-pressible wax and those fractions may be produced directly by distillation of the tar or by combining separate distillates obtained from the tar or by dividing up a single distillate obtained from the tar or by dividing distillates and combining fractions of distillates, and such fractions characterized by their wax content are subsequently free of resins, and as above stated they may or may not be free of organic basic and organic acid substances.

In the practice of this invention the fraction or fractions containing crystalline wax will be caused to be sufficiently dilute either by carrying into them low boiling substances as a result of the distilling operations or by adding gas oil or naphtha, to permit of effective dewaxing by filter-pressing in accordance with known methods, such filter-pressing preferably being performed in a plurality of stages carried out at successively lower temperatures.

In the practice of this invention any crystalline wax that is contained in a fraction containing amorphous wax and which can be removed therefrom by distillation, is removed by producing a distillate containing wax in such form that the distillate may be added to the fractions that are to be filter-pressed, without impairing the dewaxing thereof. In the practice of this invention the fraction or fractions that contain amorphous wax, freed as far as possible of crystalline wax, are dewaxed by methods dependent upon difference of specific gravity between the wax and oil in spite of the previously existing difficulty

of dewaxing tar products unless the wax was converted to crystalline form in an operation that degraded the heavier lubricating oil. Thus, in the practice of this invention the fraction or fractions containing the amorphous wax and containing heavy lubricating oil stock are dewaxed by diluting the wax-containing oil with a solvent of such specific gravity and added in such proportion that subsequent chilling will produce a wax precipitate that is in such form that it may be removed by subsidence and a residual liquid that is sufficiently heavier or lighter than all of the wax to permit such separation, and then removing the precipitated wax either by gravity settling or by means of a suitable centrifugal process and apparatus such as the process and apparatus described in Sharples Patents No. 1,232,104; No. 1,351,265 and No. 1,416,890 and No. 1,416,891. In the process and apparatus described in those patents a carrier liquid is employed and that carrier liquid may be heated and fed to the bowl at a point near the wax discharge orifice in accordance with Jones Patent No. 1,649,117. Obviously variations and modifications may be made in the centrifugal separating operation employed in the practice of my invention. The products of this operation are heavy dewaxed lubricating oil and petrolatum, both of which contain solvent which is removed by distillation before or after subsequent treatment.

If the organic basic substances and organic acid substances are removed from the fractions subjected to dewaxing treatment, prior to the dewaxing thereof, the dewaxed product is ready for final treatment; but if dewaxing is carried out prior to removal of those substances then those substances are removed from the dewaxed bodies of oil as above described, either by removing those substances in the manner described from the separate dewaxed fractions or by combining the dewaxed bodies of oil and then removing those substances from them in the manner described.

Regardless of which of the various foregoing modes of procedure is followed, the final treatment, after organic basic and organic acid substances have been removed and after dewaxing has been carried out, will be a decolorizing treatment and a dividing of the oil into bodies of oil having desired viscosity. The decolorizing may be effected in any known manner, as by acid treatment or by clay treatment or by both of such treatments, and the decolorizing treatment may be applied to separate fractions or to a single body of oil produced by bringing together a number of dewaxed fractions freed of organic acid and basic substances. The final purified product is by non-cracking distillation freed of gas oil and it may thereby be divided into a number of fractions of lubri-

cating oil respectively having different viscosities, such as spindle oil and motor oil.

In the practice of this invention the lubricating oil stock or the several lubricating oil fractions finally obtained are comparable to corresponding products obtained from good wax-bearing crude petroleum, in viscosity, flash and fire test, color, cold test, lubricating quality, and yield. The amorphous wax obtained is a hard high melting point wax; and the crystalline wax obtained, particularly after sweating, is a good quality paraffin wax of high average melting point and of good color. The phenols may as above described be recovered in a single fraction that is thick and viscous or slightly pasty or may be recovered in several parts varying from parts that are distinctly liquid to parts that are in the form of a firm paste.

In the practice of this invention most tars can be successfully refined by following a procedure in which there is obtained from the tar by careful non-destructive distillation, a single fraction containing substantially all of the wax and free of resins or a plurality of fractions which together contains substantially all of the wax and are free of resins and then subjecting the product so removed from the tar to mild acid treatment and to strong alkali treatment and to appropriate dewaxing treatment, carrying out these treatments in any desired order except that just prior to the dewaxing treatments the products so obtained from the tar must be brought into two bodies, one of which contains only crystalline wax and will contain light and medium oil and the other of which contains only wax that cannot be removed by filter-pressing and can be removed as herein described and will contain heavy oil. The treatment for the removal of organic bases and the treatment for the removal of organic acid substances can be applied to all of the products so obtained from the tar while those products exist in a single body or to separate parts of such products, the removal of organic bases prior to the removal of organic acid substances being preferable. However, variations in the tar to be refined may require slight modifications of the foregoing procedure within the spirit of this invention, and it may be necessary to carry out the separate steps in a particular order to the end that the best results will be obtained.

From the foregoing it will be apparent that in accordance with this invention the valuable products of tars are obtained without substantial loss or degradation as products of high value and possessing their valuable characteristics, the products being free of undesirable impurities and particularly impurities likely to change the character of the oil spontaneously. It will also be apparent that lubricating oils of almost any

desired viscosity are obtained from tar simply and economically with a minimum of distillation steps as contrasted with previous recovery of only a small amount of non-viscous lubricating oil and a reduced amount of wax, the lack of quantity and value of products formerly recovered being due to an intense cracking distillation not carried out by me but performed for the purpose of converting all wax to crystalline form in order to effect its removal.

At this point I describe a specific example of the practice of my invention, with the understanding that the illustrative practice of my invention so described is set forth merely to assist in the understanding of the general principles thereof and that my invention is not limited to the details so described.

Thus, in the application of my invention to the refining of tar obtained by low temperature distillation (400° C. to 600° C.) of an average German lignite, the tar, having a specific gravity of 0.948, was distilled to a residue of hard pitch in such manner as to avoid so far as possible decomposition due to heat and to carry the constituents of the tar into the distillates in practically the same form and state in which they existed in the tar. In this distillation the first cut was crude naphtha constituting 0.2% of the tar and having .0759 specific gravity and a boiling range of 30° C. to 160° C. After this cut the introduction of superheated steam to the still was begun and the amount of steam was gradually increased until the end of the distillation.

The next cut consisted of crude kerosene or light Diesel oil constituting 17.34% of the tar and having 0.925 specific gravity and 16% creosote index.

The next cut consisted of gas oil containing some crystalline wax and constituting 17.74% of the tar and having a specific gravity of 0.935, a creosote index of 22.5% and a flashpoint of 115° C.

After this cut was completed a vacuum of about 690 mm. was maintained in the still.

The next cut consisted of light wax distillate containing crystalline wax and constituting 24.91% of the tar and having 0.934 specific gravity, 13% creosote index, 162° C. flashpoint, 1.85 Engler viscosity at 50° C., and 33° C. cold test.

The next cut consisted of heavy wax distillate containing amorphous wax incapable of removal by filter-pressing. This fraction constituted 29.05% of the tar and had 0.948 specific gravity, 11.5% creosote index, 197° C. flashpoint, 5.67 Engler viscosity at 50° C., and 45° C. cold test.

The next cut consisted of resins and gummy material constituting 5.06% of the tar, which could have been left in the residue but which are advantageously kept separate from the lubricating oil fractions.

The residue consisted of hard pitch constituting 2.85% of the tar and having 81-82 Kraemer Sarnow melting point.

It is possible that during the distillation of the light wax distillate a rise and fall of specific gravity of the stream may occur. Inasmuch as the flashpoint and viscosity rise regularly through such period it is improbable that such unexpected changes of gravity are due to occurrence of cracking; and the decrease of creosote index through such period indicates that the change of specific gravity is due to change of creosote content. A similar explanation applies to the occurrence of higher specific gravity at the end of the gas oil cut than at the beginning of the light wax distillate.

The advantages of this invention are best obtained when sharp cuts are made between the several fractions. A sharp cut is particularly important between the heavy wax distillate and the resins which may be taken off as a distillate or retained in the residue. An efficient dephlegmator is recommended. The point at which this cut is made may be determined empirically with each batch or type of tar treated, by determining what percent of the tar must be left in the still at the end of the heavy wax distillate. The heavy wax distillate should contain substantially no resins and the temperature at the end of the cut can be determined by experiment as above described.

The gas-oil fraction and the light wax distillate were combined and treated with about 2% by weight of 50° Bé. sulphuric acid which separated out a sludge that included combined organic bases such as pyridine, the loss being about 1.92%.

The heavy wax distillate was similarly acid treated with a loss of 0.73%.

The acid treated fractions were then separately treated with about 5% by weight of 38° Bé. caustic soda solution at a temperature of 60° C. to 70° C. which produced a viscous dark sludge precipitate. The supernatant oil was washed in each case with a volume of water equal to 30% to 40% of the oil, the last wash water being free of reddish color. This treatment carried out 15.9% of the light distillate and 13.1% of the heavy distillate.

The sodium salts were decomposed by acid producing viscous liquid creosotes from the light distillate and gummy creosotes solid at ordinary temperature from the heavy distillate. The treatment changed the viscosity of the heavy distillate from 5.67 Engler at 50° C. to 4.16 at 50° C. because of the removal of the heavy creosotes.

In the illustrative example here described the wax in the heavy distillate appeared more crystalline after the alkali treatment, and by steam distillation with a maximum temperature of 340° C. there was removed and added to the light wax distillate a fraction having

0.911 specific gravity, 0 creosote index, 1.97 Engler viscosity at 50° C., 156° C. flashpoint, 38° C. cold test and representing 42.8% of the original heavy wax distillate. The residue of the heavy wax distillate then constituted 13.62% of the original tar and had 0.951 specific gravity, 14.75 Engler viscosity at 50° C., 2.05 Engler viscosity at 100° C., 236° C. flashpoint and 47° C. cold test. This residue out of the heavy wax distillate contained wax that could not be removed by filter-pressing and contained valuable viscous lubricating oils and was substantially free of creosotes, resins, and asphalt. While the existence of such oils in tar may have been proved by acetone extraction in a laboratory experiment, these oils were destroyed by the previously practiced operations that converted this amorphous wax to crystalline wax, the inability to remove the amorphous wax having led to the practice of such operations. However, in accordance with this invention viscous oils containing this wax which cannot be removed by filter-pressing can be successfully dewaxed on a commercial scale centrifugally. Thus, the stock containing wax incapable of removal by filter-pressing was blended with naphtha to produce a mixture comprising 30% by weight of oil and 70% of naphtha, the mixture was slowly chilled at the rate of 1° C. to 1½° C. per hour during 44 hours down to -25° C. The chilled mixture was then introduced into a Sharples centrifuge substantially of the type shown in Fig. 4 of Jones Patent No. 1,649,117, hot carrier liquid being employed. After distilling off the naphtha from the dewaxed oil solution discharged from the centrifuge, the product consisted of dark cylinder stock having a specific gravity of about unity, 3.48 Engler viscosity at 100°, 232° C. flashpoint, 272 fire-point, -2° C. cold test. This dewaxed oil represented 54.25% of the heavy amorphous stock prior to dewaxing and 7.55% of the original tar, a yield comparable to that obtained from good average crude petroleum. The balance of the heavy amorphous dewaxing stock was petrolatum having a melting point of 54° C. and representing 6.07% of the original tar, this being a hard amorphous wax, it may be refined and used commercially.

Crystalline wax stock comprising gas oil, the light wax distillate, and the distillate taken from the original amorphous fraction and constituting 44.48% of the original tar, was dewaxed by filter-pressing in two stages at respectively 16° C. and -5° C. The paraffin obtained comprised 23.78% of the stock dewaxed or 10.58% of the original tar, had a melting point of 48°-49° C. before sweating and 54° C. after sweating. The sweat oils were available for re-cycling. The oil obtained by removal of crystalline wax and containing gas oil had 0.945 specific gravity, 130° C. flashpoint, 1.64 Engler viscosity at

50° C., -4° C. cold test. This light dewaxed oil stock was mixed with the heavy dewaxed oil stock and the final dewaxed lubricating oil stock was refined with about 5% of 66° Bé. sulphuric acid with a loss of 7.8% of the treated oil. The acid treated oil was neutralized with about 2% of dry soda ash at 80-90° C., filtered to remove excess soda ash and reaction products and about 10% of bleaching clay was added. Thereafter distillation with steam and under vacuum produced three fractions.

(1) A gas oil fraction constituting 21.11% of the dewaxed stock and 8.27% of the original tar and having 0.904 specific gravity, 106° C. flashpoint, -2° C. cold test.

(2) A spindle oil fraction constituting 25.3% of the dewaxed oil stock and 9.9% of the original tar and having 0.920 specific gravity, 150° C. flashpoint, 1.85 Engler viscosity at 20° C. and -1° C. cold test.

(3) A still residue containing the decolorizing clay which was removed by filtration giving a finished viscous internal combustion motor oil, constituting 53.5% of the dewaxed stock and not less than 20% of the original tar and having 0.970 specific gravity, 218° C. (open cup) flashpoint, 245° C. fire-point, 8.1 Engler viscosity at 50° C., 1.7 Engler viscosity at 100° C., 0° C. cold test, 0.12% organic acidity expressed in SO₃, 0.11% ash, traces of soft asphalt, red in transmitted light, green in reflected light, traces only of creosote, and free of hard asphalt.

The foregoing exemplary application of this invention indicates by illustration many conditions, causes, effects and results occurring in the practice of this invention, but it is to be understood that within the spirit of this invention many modifications may be made. Such modifications include the above described variations in the points at which the several treatments may be applied and the variations in the formation of separate fractions.

Also, the fraction containing amorphous wax may be a residue instead of a distillate, particularly when the tar is substantially free of resins. For example, some tars obtained from oil shale may be treated to produce a distillate containing crystalline wax and a residue containing amorphous wax so long as the preparation for the dewaxing operations consists of forming a crystalline-wax-containing fraction and an amorphous-wax-containing fraction, both substantially free of resins. Another possible modification is the removal of organic acid and basic substances by alcohol washing instead of caustic treatment and mild acid treatment.

To assist in the understanding of this invention there are annexed hereto drawings in which:

Fig. 1 shows diagrammatically a flow sheet in which is indicated the operations described in the illustrative example set out in detail

above as a specific application of this invention;

Fig. 2 shows diagrammatically a flow sheet in which is indicated one of several possible modifications of the sequence of operations embodying this invention; and

Fig. 3 shows diagrammatically a flow sheet in which is indicated another of the several possible modifications of the sequence of the operations embodying this invention.

While I have shown in the drawings several possible modifications of operations embodying this invention it is to be understood that still other modifications may be made within the spirit of this invention. It seems preferable, in most cases, to remove organic acid substances prior to dewaxing when the dewaxing is to be carried out by continuous centrifugal separation, because those substances, particularly if they contain heavy creosotes, are likely to interfere with continuous discharge of the wax from the centrifuge.

There is at present considerable scientific discussion concerning the actual form or characteristics of wax. However, wax is called "crystalline" herein whenever it is of such character that it can be removed by filter-pressing, and wax is called "amorphous" herein when it is of such character that it cannot be successfully removed by filter-pressing and can be removed by methods depending upon difference of specific gravity, although from a scientific point of view so-called "amorphous" wax may consist of crystals of smaller size. In the claims, the expressions "containing pressible wax" and "containing amorphous wax" are used in the sense above described, although the tar fractions referred to may or may not contain organic basic and acid substances in addition to oil.

In the claims the expression "carbonaceous solids" is intended to include solids which may be composed wholly of carbonaceous material and also solids which include carbonaceous material but also contain, even in a large proportion, solid constituents which are not in themselves carbonaceous.

I claim:

1. In the refining of tar obtained by distillation of carbonaceous solids, the steps comprising by non-destructive distillation separating from the tar and from the resins and pitches thereof a part of the tar containing substantially all of the lubricating-oil constituents of the tar and substantially free of resin and by similar distillation dividing that part of the tar so withdrawn into a fraction containing pressible wax and a fraction containing non-pressible wax, and separately dewaxing said fractions respectively by methods suitable to the removal of pressible wax and non-pressible wax.

2. In the refining of tar obtained by distillation of carbonaceous solids, the steps

comprising by non-destructive distillation separating from the tar and from the resins and pitches thereof a part of the tar containing substantially all of the wax constituents of the tar and substantially free of resin and by similar distillation dividing that part of the tar so withdrawn into a fraction containing pressible wax and a fraction containing non-pressible wax, and separately dewaxing said fractions respectively by methods suitable to the removal of pressible wax and non-pressible wax.

3. In the refining of tar obtained by distillation of carbonaceous solids, the steps comprising by non-destructive distillation separating from the tar and from the resins and pitches thereof a part of the tar containing substantially all of the lubricating-oil constituents of the tar and substantially free of resin and by similar distillation dividing that part of the tar so withdrawn into a fraction containing pressible wax and a fraction containing non-pressible wax, separately dewaxing said fractions respectively by methods suitable to the removal of pressible wax and non-pressible wax, and removing from the part so separated from the tar organic acid substances and organic basic substances.

4. In the refining of tar obtained by distillation of carbonaceous solids, the steps comprising by non-destructive distillation separating from the tar and from the resins and pitches thereof a part of the tar containing substantially all of the wax constituents of the tar and substantially free of resin and by similar distillation dividing that part of the tar so withdrawn into a fraction containing pressible wax and a fraction containing non-pressible wax, separately dewaxing said fractions respectively by methods suitable to the removal of pressible wax and non-pressible wax, and removing from the part so separated from the tar organic acid substances and organic basic substances.

5. In the refining of tar obtained by distillation of carbonaceous solids, the steps comprising by non-destructive distillation separating from the tar and from the resins and pitches thereof a fraction containing non-pressible centrifugally-removable wax and substantially free of resins, diluting said fraction with a solvent added in such proportion and of such specific gravity that upon chilling of the mixture there will be formed a discontinuous wax precipitate and a residual liquid solution having a specific gravity that differs in the same respect from the specific gravity of all of the wax, chilling said mixture and thereby precipitating wax therein, and continuously separating precipitated wax centrifugally from said chilled mixture.

6. In the refining of tar obtained by distillation of carbonaceous solids, the steps comprising by non-destructive distillation sepa-

rating from the tar and from the resins and pitches therof a fraction containing non-pressible centrifugally-removable wax and substantially free of resins, diluting said fraction with a solvent added in such proportion and of such specific gravity that upon chilling of the mixture there will be formed a discontinuous wax precipitate and a residual liquid solution having a specific gravity that differs in the same respect from the specific gravity of all of the wax, chilling said mixture and thereby precipitating wax therein, continuously separating precipitated wax centrifugally from said chilled mixture, removing organic basic and acid substances from said fraction, and thereby producing high viscosity low cold-test lubricating oil from the tar.

7. In the refining of tar obtained by distillation of carbonaceous solids, the steps comprising by non-destructive distillation separating from the tar and from the resins and pitches thereof a fraction containing pressible wax and a fraction containing amorphous wax and substantially free of resins, and in any order removing organic acid substances from that part of the tar constituted by said fractions and separately dewaxing said fractions respectively by methods suitable to the removal of pressible wax and amorphous wax.

8. In the refining of tar obtained by distillation of carbonaceous solids, the steps comprising by non-destructive distillation separating from the tar and from the resins and pitches thereof a fraction containing pressible wax and a fraction containing amorphous wax and substantially free of resins, and in any order removing organic basic substances from that part of the tar constituted by said fractions and separately dewaxing said fractions respectively by methods suitable to the removal of pressible wax and amorphous wax.

9. In the refining of tar obtained by distillation of carbonaceous solids, the steps comprising by non-destructive distillation separating from the tar and from the resins and pitches thereof a fraction containing pressible wax and a fraction containing amorphous wax and substantially free of resins, and in any order removing organic basic substances and organic acid substances from that part of the tar constituted by said fractions and separately dewaxing said fractions respectively by methods suitable to the removal of pressible wax and amorphous wax.

10. In the refining of tar obtained by distillation of carbonaceous solids, the steps comprising by non-destructive distillation separating from the tar and from the resins and pitches thereof a fraction containing pressible wax and a fraction containing amorphous wax and substantially free of

resins, subjecting that part of the tar constituted by said fractions to mild acid treatment to remove organic basic substances, and separately dewaxing said fractions respectively by methods suitable to the removal of 70 pressible wax and amorphous wax.

11. In the refining of tar obtained by distillation of carbonaceous solids, the steps comprising by non-destructive and distillation separating from the tar and from the resins and pitches thereof a fraction containing pressible wax and a fraction containing amorphous wax and substantially free of resins, subjecting that part of the tar constituted by said fractions to treatment with strong alkali 80 solution to remove organic acid substances therefrom, and separately dewaxing said fractions respectively by methods suitable to the removal of pressible wax and amorphous wax.

12. In the refining of tar obtained by distillation of carbonaceous solids, the steps comprising by non-destructive distillation separating from the tar and from the resins and pitches thereof a fraction containing pressible wax and a fraction containing amorphous wax and substantially free of resins, removing organic acid substances from that part of the tar constituted by said fractions, and separately dewaxing the fractions freed 95 of organic acid substances, respectively by methods suitable to the removal of pressible wax and amorphous wax.

13. In the refining of tar obtained by distillation of carbonaceous solids, the steps comprising by non-destructive distillation separating from the tar and from the resins and pitches thereof a fraction containing pressible wax and a fraction containing amorphous wax and substantially free of resins, removing organic acid and basic substances from that part of the tar constituted by said fractions, and separately dewaxing said fractions freed of said substances, respectively by methods suitable to the removal 110 of pressible wax and amorphous wax.

14. In the refining of tar obtained by distillation of carbonaceous solids, the steps comprising by non-destructive distillation separating from the tar and from the resins and pitches thereof a fraction containing pressible wax and a fraction containing amorphous wax and substantially free of resins, dewaxing the first fraction by filter pressing, dewaxing the second fraction by 115 subsidence, combining and decolorizing the resulting dewaxed bodies of oil, and fractionating the combined dewaxed product to obtain lubricating oil.

15. In the refining of tar obtained by distillation of carbonaceous solids, by non-destructive distillation separating from the tar and from the resins and pitches thereof a fraction containing centrifugally removable wax, removing organic b .ses from said frac- 130

- tion by mild acid treatment, then removing creosote from said fraction, and centrifugally dewaxing the fraction free of creosote.
16. In the refining of tar derived from lignite by low temperature distillation, the steps comprising by non-destructive distillation separating from the tar and from the resins and pitches thereof, a fraction comprising amorphous wax and viscous lubricating oil and substantially free of resin, removing organic acid substances and organic basic substances from said fraction, diluting and chilling and centrifugally dewaxing said fraction.
- 15 17. In the refining of tar derived from lignite by low temperature distillation, the steps comprising by non-destructive distillation separating from the tar and from the resins and pitches thereof, a fraction comprising amorphous wax and viscous lubricating oil and substantially free of resin, subjecting said fraction to mild acid treatment and to alkali treatment, and then diluting and chilling and centrifugally dewaxing said fraction.
- 25 18. In the refining of tar obtained by distillation of carbonaceous solids, the steps comprising by non-destructive distillation separating from the tar and from the resins and pitches thereof a fraction that is substantially free of resins and contains wax that is non-pressible and is removable by methods depending upon difference of specific gravity, diluting said fraction with a solvent added in such proportion and of such specific gravity that upon chilling of the mixture there will be formed a discontinuous wax precipitate and a residual liquid solution having a specific gravity that differs in the same respect from the specific gravity of all of the wax, chilling said mixture and thereby precipitating wax therein, and separating precipitated wax from said chilled mixture by difference of specific gravity.
- 30 19. In the refining of tar obtained by distillation of carbonaceous solids, the steps comprising by non-destructive distillation separating from the tar and from the resins and pitches thereof a fraction that is substantially free of resins and contains wax that is non-pressible and is removable by methods depending upon difference of specific gravity, diluting said fraction with a solvent added in such proportion and of such specific gravity that upon chilling of the mixture there will be formed a discontinuous wax precipitate and a residual liquid solution having a specific gravity that differs in the same respect from the specific gravity of all of the wax, chilling said mixture and thereby precipitating wax therein, separating precipitated wax from said chilled mixture by difference of specific gravity, removing organic basic and acid substances from said fraction, and thereby producing high viscosity low cold-test lubricating oil from the tar.
- 35 20. In the refining of tar obtained by distillation of carbonaceous solids, by non-destructive distillation separating from the tar and from the resins and pitches thereof a fraction containing non-pressible wax that is removable by difference of specific gravity, removing organic bases from said fraction by mild acid treatment, then removing creosote from said fraction by alkali treatment, and dewaxing the fraction.
- 40 21. In the refining of tar derived from lignite by low temperature distillation, the steps comprising by non-destructive distillation separating from the tar and from the resins and pitches thereof, a fraction comprising amorphous wax and viscous lubricating oil and substantially free of resin, and in any order removing organic acid substances and organic basic substances from said fraction by any method suitable to the removal of amorphous wax and diluting and chilling and dewaxing said fraction by difference of specific gravity.
- 45 In testimony whereof, I have signed my name to this specification.

CERTIFICATE OF CORRECTION.

Patent No. 1,791,052.

Granted February 3, 1931, to

JEAN H. BREGI.

It is hereby certified that error appears in the printed specification of the above numbered patent requiring correction as follows: Page 1, line 37, for the misspelled word "viscocity" read viscosity; page 2, line 58, for "no-cracking" read non-cracking; page 8, line 41, claim 8, for "separately" read separately; same page, line 74, claim 11, strike out the word "and"; page 9, line 76, claim 20, after "fraction" insert the words by any method suitable to the removal of amorphous wax, and lines 86 and 87, claim 21, strike out the words "by any method suitable to the removal of amorphous wax"; and that the said Letters Patent should be read with these corrections therein that the same may conform to the record of the case in the Patent Office.

Signed and sealed this 14th day of April, A. D. 1931.

**M. J. Moore,
Acting Commissioner of Patents.**
